UNITED STATES PATENT OFFICE.

WILFRED SHURTLEFF, OF MOLINE, ILLINOIS.

FUEL-FEEDING DEVICE.

1,244,553.

Specification of Letters Patent. Patented Oct. 30, 1917.

Application filed November 22, 1916. Serial No. 132,791.

To all whom it may concern:

Be it known that I, WILFRED SHURTLEFF, a citizen of the United States, and a resident of Moline, in the county of Rock Island and 5 State of Illinois, have invented certain new and useful Improvements in Fuel-Feeding Devices, of which the following is a specification.

My invention relates to a fuel feeding device 10 vice adapted particularly for controlling the feed of oil to carburetors of vehicle gas engines where the carburetor is above the level of the oil supply tank.

Among the important objects of the invention are to produce a device of this class 15 comprising only a few simple parts which will efficiently coöperate to control the feeding; to cause a common container to act both as a float and for receiving and storing fuel 20 to be fed to the carburetor while the main container is being refilled; to provide improved means for preventing wavering or hesitating movement of the float-container member and to cause positive and quick 25 action thereof and movement to its extreme positions to quickly actuate valve mechanism for controlling the refilling of the main container, recharging of the storage container, and the connection with the containers of the 30 outlet with which the carburetor is connected, my improved means operating magnetically; to provide construction and arrangement which will enable the device to be readily taken apart for inspection, repair 35 or cleaning purposes; and in general to provide a simple, inexpensive and highly efficient device of this class.

On the accompanying drawing I show a device which embodies the various features 40 of my invention. On this drawing

Figure 1 is a vertical diametral sectional view of the device, and

Fig. 2 is a top view thereof.

The outer or main container 5 is formed 45 by the cup-shaped halves 6 and 7 fitted together edge to edge and secured by means of opposed lugs or flanges 8 and 9 and bolts 10, a suitable gasket 11 being interposed to prevent leakage. The upper half has the 50 threaded opening 12 for receiving piping 13 which carries oil from a supply tank (not shown) and which in the vehicle is situated below the level of the carburetor. In order to strain the fuel before entering the container a screen 14 is secured at its bottom and side edges to the inside of the container 55 in front of the inlet 12 and with its top edge

spaced away from the container wall in order that if the screen should become clogged with dirt and impurities, the oil can 60 still flow into the container over the top of the screen. The container halves can be in the form of castings but are preferably drawn from sheet metal to be light and 65 strong.

At the center of the bottom of the container is the threaded boss 15 in which is secured the fitting 16 from which a pipe 17 extends up axially into the container 5, the outer end of the fitting being threaded to receive a coupling cap 18 for securing a pipe 19 which leads to the carburetor (not shown). Within the main container 5 is the cylindrical member 20 which serves both as a float and as a storage container for fuel. The 75 member is preferably formed by cylindrical cup-shaped halves 21 and 22 secured and sealed together at their edges. At the center of its lower wall the member 20 has the boss 23 whose opening 24 receives the pipe 17 80 already referred to, the container 20 being slidable on this pipe. Just above the fitting 16 the pipe 17 has port holes 25 which, when the container 20 is down, are open only to such container, and when the container is 85 up the ports are open to the outer container 5.

Extending downwardly from the upper wall of the container 20 is a pipe 27 and seated and secured in the upper end of this 90 pipe is a plug 28 in which the lower end of the hollow valve stem 29 is secured, the container 20 being at all times open to the atmosphere through this stem. Fitted in the top of the container 5 at the center 95 thereof is a block 30 having the cylindrical valve passageway 31 through which the stem 29 extends. The block has the internally threaded lug 32 extending therefrom for receiving a pipe which leads to the manifold 100 of the vehicle engine (not shown). The interior of the lug is connected by a fine passageway 33 with the valve passageway 31. Near its upper end the valve stem has the enlarged cylindrical section 34 which forms 105 a valve, the lower edge 35 of this valve being preferably tapered as shown in order that the valve may readily reenter the passageway 31 after being raised therefrom. Below the valve and spaced a distance therefrom 110 is a guide collar 36 which is of slightly less diameter than the passageway 31 in order that the suction passageway 33 may at all times be in connection with the container 5.

When the container 20 is in its lower position, as shown in full lines, the valve 34 is within the passageway 31 and this passageway is closed against atmosphere and the suction of the manifold is effective in the container 5. When the container 20 is raised the valve 34 will be lifted above the passageway 31 so that the container 5 can vent to the atmosphere and the suction effect in the container will be destroyed.

During operation of the device the upward movement of the container 20 is controlled by the upward pressure of the fuel in the outer container 5, and its downward movement is controlled by gravity. I provide improved means in the form of magnetic mechanism for preventing wavering or hesitating movement of the member 20 and to insure positive and rapid movement thereof to either its upper or lower position, thereby causing the various valves and ports to be quickly opened or closed to insure efficient feeding operation of the device and re-filling thereof. Mounted on posts 37 and 38 extending upwardly from container 5 is a permanent horse-shoe magnet 39 between whose poles the upper end of valve stem 29 extends. On the stem are upper and lower armatures or keepers 40 and 41, in the form of washers. The armature 41 rests on the valve 34 and the armature 40 is spaced from the armature 41 by a sleeve 42 on the stem, a cotter pin 43 above the armature 40 holding it in place. A plate 44 held down by a screw 45 clamps the magnet to the posts and permits adjustment thereof relative to the armatures.

Describing now the operation, the down position of the member 20 is shown in full lines, there being insufficient fuel in the outer container 5 to raise and float the member 20. The boss 23 is below ports 25 and shuts off flow of fuel from the container 5 to the carburetor which receives its fuel from the container 20 through the ports 25. The armature 43 is in contact with the magnet poles and the attraction assists gravity in holding the container 20 in its lower position. The valve 34 being within the passageway 31 shuts off the container 5 from atmosphere so that manifold suction is effective in the container 5 to create vacuum for drawing up fuel from the supply tank into the container. As soon as the fuel reaches a sufficient level in the container 5 the magnetic force and the force of gravity on the container 20 will be overcome and then the container 20 will be raised, and during such raising the magnetic attraction of the magnet on the upper armature 40 is diminished and the attraction on the lower armature 41 is increased and as soon as the neutral line is passed the lower armature is quickly attracted and the container 20 quickly raised to its upper position. As

shown by the dotted lines the boss 23 is now above the ports 25 to close them to container 20 and fuel will flow from the outer container 5 to the carburetor, and so long as the level in container 5 is above the upper end of pipe 17 and above the level of fuel in container 20, fuel will flow through the pipe into the inner container 20 to replenish this container, and the valve 34 being raised out of the passageway 31 suction is no longer effective in container 5 and this container is open to the inlet of air under atmospheric pressure, this permitting the fuel to flow from the container 5 into container 20 which is also open to air through the hollow valve stem. As soon as container 20 has been filled sufficiently so that the added weight will overcome the flotation force of fuel in container 5 and the attraction of the lower armature 41 the container 20 will drop and will again shut off container 5, and container 5 will be re-closed to atmosphere and re-connected with the manifold suction to be replenished with fuel. Without the magnet and armatures the fuel flotation pressure and gravity would reach a balance point during filling or emptying of the containers and during such balance period the operation of the container 20 would be uncertain particularly when the vehicle is traveling, and there would not be efficient valving. However, with the magnet and armatures the member 20 is held for a time against the fuel pressure and gravity until these forces become sufficiently strong to disconnect the respective armature from the magnet whereupon the freed force will suddenly shift the member 20 and bring the other armature into the strong field of the magnet to be quickly attracted against the magnet. This insures positive and rapid movements of the container 20 to its upper or lower positions with correspondingly positive and quick control of the ports and valve. The magnet is of sufficient strength to hold the armatures against jarring of the vehicle. The inner container 20 being always open to atmosphere through the hollow valve stem 29 fuel can readily flow into or out of said container. It will be noted that the pipe 27 is of larger diameter than the hollow valve stem 29 and extends downwardly close to the stem pipe 17. This construction prevents escape of fuel through the valve stem which might be caused by foaming of the fuel flowing upwardly from the pipe 17. Such foaming fuel is received by the pipe 27 in which the bubbles have a chance to break so that the released fuel may flow back into the container and the air escape upwardly through the valve stem.

The device of my invention consists of few and simple parts. The arrangement involving the use of a single member acting as a port and valve controlling float and as an

auxiliary reservoir is a decided improvement over prior structures in which the reservoir and float are separate members. By removing the bolts 10 the halves of the outer container can be readily separated and the inner container 20 withdrawn, and by withdrawing the pin 43 the armatures can be removed from the valve stem. My improved device can therefore be inexpensively manufactured and kept in perfect condition with little labor and expense.

I do not desire to be limited to the exact construction, arrangement and operation shown and described as changes and modifications can no doubt be made which would still come within the scope of the invention.

I claim as follows:

1. In a fuel feed device of the class described, the combination of an outer container having a fuel inlet, a pipe extending upwardly into said container and adapted at its outer end for connection with a carburetor, said pipe having ports, a closed inner container receiving and slideable on said pipe to close and open said ports, said pipe being open to said inner container, a suction outlet and an atmosphere inlet for said outer container, and a valve operated by the shifting of said inner container to control said atmosphere inlet.

2. In a fuel feeding device of the class described, the combination of an outer fuel container, an inner container free to be shifted by gravity and the floating force of fuel in the outer container, a carburetor supply outlet connected with the inner container, valve means controlled by the movement of said inner container to connect the outer container either with the inner container or with said outlet, said outer container having an inlet for fuel, a suction outlet and atmosphere inlet for said outer container, and a valve controlled by the movement of said inner container to control the atmosphere inlet.

3. In a fuel feeding device of the class described, the combination of an outer fuel container, an inner container free to be shifted by gravity and the floating force of fuel in the outer container, a carburetor supply outlet connected with the inner container, valve means controlled by the movement of said inner container to connect the outer container either with the inner container or with said outlet, said outer container having an atmosphere inlet and a permanently open suction outlet, and a valve shifted by said inner container and adapted in one position to close the atmosphere inlet to permit suction to be effective in the outer container and in another position to open the atmosphere inlet to connect the outer container with atmosphere and to destroy the suction.

4. In a fuel feeding device of the class

described, the combination of an outer container having a fuel inlet and a fuel outlet, an inner movable container responsive to the flotation force of fuel in the outer container, said inner container having connection with said outlet, means controlled by the movement of said inner container for controlling the flow of fuel from the outer container to said outlet or into said inner container, and means for automatically replenishing said outer container.

5. In a fuel feeding device of the class described, the combination of an outer container having a fuel inlet and a fuel outlet, an inner movable container responsive to the flotation force of fuel in the outer container, said inner container having connection with said outlet, means controlled by the movement of said inner container for controlling the flow of fuel from the outer container to said outlet or into said inner container, said outer container having an atmosphere inlet and having a suction outlet adapted for connection with a suction producing device, and valve mechanism moved with said inner container to control said atmosphere inlet.

6. In a fuel feeding device of the class described, the combination of an outer container having a fuel inlet and a fuel outlet, an inner movable container responsive to the flotation force of fuel in the outer container, said inner container having connection with said outlet, means controlled by the movement of said inner container for controlling the flow of fuel from the outer container to said outlet or into said inner container, said outer container having an atmosphere inlet and having a permanently open suction outlet adapted for connection with a suction device, and valve mechanism controlled by said inner container to close or open said atmosphere inlet.

7. In a fuel feed device of the class described, the combination of a fuel container having a fuel inlet and a fuel outlet, a float member within the container, valve mechanism operated by the float member to control the connection of said container with said outlet, and magnetic mechanism operable to first resist and then to assist the movements of said float member.

8. In a fuel feed device of the class described, the combination of a fuel container having a fuel inlet and a fuel outlet, a float member within the container, valve mechanism operated by the movements of said float member to control the connection of said container with said outlet, armatures connected with said float member, and a magnet having its poles interposed between said armatures and cooperating therewith to first resist and then to assist the movements of said float member.

9. In a fuel feeding device of the class de-

scribed, the combination of a container having a fuel inlet and a fuel outlet, a float member within the container, valve mechanism operated by the movements of said float member to control the connection of said container with said outlet, the top of said container having a passageway for the entrance of air to the container, a permanently open suction outlet from said container adapted for connection with a suction source, a valve stem extending from the float member through said passageway, and a valve on said valve stem for controlling the opening and closing of said air passageway.

10. In a fuel feeding device of the class described, the combination of a container having a fuel inlet and a fuel outlet, a float member within the container, valve mechanism operated by the movements of said float member to control the connection of said container with said outlet, the top of said container having an inlet passageway for air, a suction outlet from said passageway adapted for connection with a suction source, a stem extending upwardly from said float member through said passageway, a valve on said stem for controlling the inlet of air through said passageway, upper and lower armatures on said stem, and a magnet having its poles interposed between said armatures and coöperating with said armatures to effect positive rapid shifting of said float member from one position to another.
15. 11. In a fuel feeding device of the class described, the combination of an outer container having a fuel inlet, a pipe extending upwardly in said container and adapted at its outer end for connection with a carbureter, said pipe having ports, an inner container receiving and slideable on said pipe to close and open said ports, said ports being disconnected from said outer container and connected with the inner container when said inner container is down and said ports being connected with said outer container and disconnected from the inner container when said inner container is up, said pipe being permanently open at its upper end to said inner container, a suction outlet and an atmosphere inlet for said outer container, and a valve operated by the shifting of the inner container to control said atmosphere inlet.
20. 12. In a fuel feed device, the combination of an outer container, means for varying the level of fuel therein, an inner container within said outer container, a pipe extending upwardly from the bottom of said outer container and through the bottom of and into the inner container and open at its upper end to the inner container, said pipe having ports, said inner container shifting

along said pipe with a varying level of fuel in said outer container, and the bottom of said inner container coöperating with said ports to disconnect the outer container from said pipe and to connect the inner container with said pipe when said inner container is down and to connect said outer container with said pipe and to disconnect the inner container therefrom when the inner container is up whereby fuel may flow from the outer container into the inner container when said inner container is up and whereby said pipe is fed alternately from said containers, the outer end of said pipe being adapted for connection with a device to be supplied with fuel.

13. In a fuel feed device, the combination of an outer container, means for varying the level of fuel therein, an inner container within said outer container, a pipe extending upwardly from the bottom of said outer container and through the bottom of and into the inner container and open at its upper end to the inner container, said pipe having ports, said inner container shifting along said pipe with a varying level of fuel in said outer container, and the bottom of said inner container coöperating with said ports to disconnect the outer container from said pipe and to connect the inner container with said pipe when said inner container is down and to connect said outer container with said pipe and to disconnect the inner container therefrom when the inner container is up whereby fuel may flow from the outer container into the inner container when said inner container is up and whereby said pipe is fed alternately from said containers, the outer end of said pipe being adapted for connection with a device to be supplied with fuel, said inner container being permanently connected with the atmosphere, an air inlet for said outer container, and valve means operated by said inner container for controlling the inflow of air through said inlet to said outer container.

14. In a fuel feed device, the combination with a container having a fuel outlet, a float member shiftable within said container, valve mechanism operated by said float to control the outflow of fuel from the container, a valve stem carried by said float member, a valve on said stem for controlling the inflow of air to said container, armatures on said stem, and a magnet having its poles projecting between said armatures to coöperate therewith to assist said float in controlling said outflow valve mechanism.

In witness whereof I hereunto subscribe my name this 17 day of November, A. D., 1916.

WILFRED SHURTELL.
